CLAMP COMB

James E. McArthur, San Francisco, Calif.

Application July 21, 1945, Serial No. 606,303

4 Claims. (Cl. 132—23)

1

This invention relates to clamp combs and more particularly to hair combs having cooperating movable and immovable teeth.

Among the objects of the invention is to cause the teeth of the comb to grip the hair and hold the comb and the hair in adjusted position.

Another object is to provide an aid to hair dressers in the preliminary arrangement of locks of hair for permanent waving, curling and thermo-setting human hair.

A further object is to simplify the structure and mode of operation of mechanical combs for utility or decoration, in arranging coiffures.

Other objects and advantages will appear as the description progresses. In the specification and the accompanying drawings the invention is disclosed in its preferred form. But it is to be understood that it is not limited to this form; because it may be embodied in modifications within the spirit of the invention, as defined in the claims following the description.

In the one sheet of drawings:

Fig. 1 is a rear elevation of a clamping comb constructed in accordance with this invention.

Fig. 2 is a plan view from above of the same.

Fig. 3 is an enlarged detail in vertical section on the line III—III, Fig. 1.

Fig. 4 is a fragmentary enlarged detail in rear elevation, of the spring clamping element.

Fig. 5 shows a modified form of the invention.

In detail the structure illustrated in the drawings, referring first to Fig. 2, comprises the arcuate back bow 1, having the inwardly flanged top and bottom edges 2, 3.

The stationary teeth 4 are integral with the grid 5 confined within the flanged edges 2, 3. This strip has a series of interspaced openings 6 therethrough, between the stationary teeth 4.

The movable teeth 7 project through these openings and are integral with the sliding plate 8, that is guided in the longitudinal grooves formed in the edges 2, 3.

The movable teeth 7 are normally forced against the stationary teeth 4 by the expansion of the spring 9, located at the mid-portion of the back bow 1, on the longitudinal axis of the plate 8. The opposite ends of this spring engage the lug 10 on the plate 8 and the transverse lug 11 on the grid 5 adjacent a stationary tooth, respectively. These springs may be duplicated at intervals to increase the tension.

Referring to Figs. 1, 2, the manual grips 12, 13 of the grid 5 and the plate 8 project beyond the opposite ends of the back bow 1 respectively. The grip 13 remains stationary, while the grip 12

is slidable relatively thereto, for overcoming the tension of the spring 9 and separating the movable teeth 7 from the stationary teeth 4.

The invention operates substantially as follows: The grips 12, 13 are grasped between the thumb and forefinger of the operator and pressed toward each other. This overcomes the tension of the spring 9 and separates the teeth equidistant from each other. The teeth are then inserted 10 into the hair against the scalp and pushed downwardly to the desired position. When the grips 12, 13 are released the spring expands and pushes the movable teeth against the stationary teeth and securely fixes the comb in the desired position, 15 due to frictional clamping action of the teeth against the mass of hair therebetween. The comb is removed or readjusted by reversing the action by pressure applied to the grips 12, 13, as described.

20 The comb is assembled by passing the teeth 7 on the plate 8, through the openings 6 in the grid 5, until the plate and grid lie in parallel relation. Thus assembled they are pushed endwise into the back bow 1. The grid 5 being slightly wider than the plate 8, the latter has a free longitudinal sliding action within the bow 1, relative to the grid 5. The grip 12 is then cemented to the end of the plate 8.

25 The spring 9 may be assembled on the lugs 10, 30 11 before the insertion of the grid and plate 5, 8 in the back bow 1, or it may be so assembled after the insertion.

35 For professional use, where ornamentation is not a consideration, the ends 2xm 3x may be formed on the grid 5 as shown in Fig. 5, where they will perform the same function as the back bow 1.

40 The present design of the invention is adaptable to fabrication in molded plastics, or die stamping in metal by appropriate modification of the dimensions of the material desired.

In plastic or metal there is sufficient flexibility 45 to permit the back bow 1 being forced over the beveled edges of the grid 5, instead of assembling by sliding this grid 5 and plate 8 endwise into the bow 1, as above described. If assembled by snapping the back bow onto the grid 5, the grip 12 can be made integral with the plate 8.

46 The grips 12, 13 and the front of the back bow 50 1, may be ornamented with jewels or otherwise decorated for personal adornment.

Having thus described this invention what is claimed and desired to secure by Letters Patent is:

1. A clamp comb comprising a grid having

3

lateral openings therethrough; stationary teeth on said grid adjacent said openings; a slidable plate longitudinally guided within said grid and having teeth thereon projecting through said openings in the grid in movable relation to said stationary teeth on the grid; and spring means interposed between said grid and plate and normally forcing said grid teeth and plate teeth together.

2. A clamp comb comprising a grid having lateral openings therethrough; stationary teeth on said grid adjacent said openings and in offset relation to and parallel with the plane of said grid; a plate longitudinally slid able and guided within said grid and having offset teeth projecting through said openings in the grid and aligning with said stationary teeth on the grid; and spring means interposed between said grid and plate and normally forcing said teeth together.

3. A clamp comb comprising a grid having longitudinal guides on its opposite edges with interspaced lateral openings through said grid; stationary teeth on said grid adjacent said openings and in offset relation to and parallel with the plane of said grid; a plate longitudinally slid able in said guides on the grid and having offset teeth projecting through said openings in the grid and aligning with said stationary teeth; and a spring interposed in said plate between a

4

tooth on the grid and a tooth on the plate and normally urging the teeth on the plate against the teeth on the grid.

5. A clamp comb comprising a grid having overhanging longitudinal edges with interspaced lateral openings through said grid; stationary teeth integral with said grid adjacent the ends of the openings in said grid and having their edges in offset relation to and parallel with the plane of said grid; a plate longitudinally slid able within the overhanging edges of said grid and projecting beyond one end of said grid and having thereon offset teeth projecting through said openings in the grid and aligning with said stationary teeth on the grid; and a spring interposed in said plate between a tooth on the grid and a tooth on the plate and normally urging the teeth on the plate against the teeth on the grid.
